RECEPTACLE FOR BACKS OF HAIR COMBS

Anthony J. Fabis, Chicago, Ill.

Application July 2, 1948, Serial No. 36,631

2 Claims. (Cl. 132—79)

1

My invention relates to hair combs of the type disclosed in my copending application, Serial No. 770,646, filed September 26, 1947, now Patent No. 2,497,983 and wherein the comb back is provided with a receptacle for the reception therein of a number of small toilet articles, such as bobby pins, hairpins, straight pins, safety pins, or the like.

With the foregoing in view, an object of my invention is to provide an improved receptacle for a comb back of the class described.

A further object is to provide an improved receptacle wherein the comb back and the cover therefor are formed to cooperate with each other to provide a closed receptacle which is readily slidable to and from open and closed positions.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is a perspective view of the device according to the invention, the receptacle being shown in a partially open position;

Figure 2 is an elevational view showing the receptacle in the closed position;

Figure 3 is a transverse vertical sectional view taken substantially on the plane of the line 3—3 of Figure 2;

Figure 4 is a bottom plan view of the cover for the receptacle apart from the rest of the structure;

Figure 5 is an enlarged plan view of the comb apart from the cover, parts being broken away and parts being shown in horizontal section.

Referring specifically to the drawing, wherein like reference characters have been used throughout the several views to designate like parts, 10 designates generally any suitable hair comb comprising a back 11 and a plurality of depending teeth 12. The comb back 11 is preferably formed with a substantially flat intermediate portion comprising an upper edge 13. As will appear hereinafter, the edge 13 defines the floor of a receptacle. Opposite end portions of the edge 13 are upwardly directed to provide buttresses 14 which define the end walls of a receptacle. Opposite sides of the comb back 11 below the plane of the edge 13 are formed to provide a pair of laterally-aligned and laterally-oppositely-directed grooves which extend longitudinally of the

2

comb back and which are generally indicated by the reference character 15. Each groove 15 comprises a relatively deep central portion 16 which is generally located between the buttresses 14, and relatively shallow end portions 17. The shallow end portions 17 and deep portions 16 merge with shoulders 18, best seen in Figure 5. The shallow portions 17, at at least one end of the groove 15, are formed with laterally outwardly-directed bosses 19 providing latch dogs. The purpose of the particular groove structure just described will be apparent hereinafter.

To complete the receptacle partially defined by the edge 13 and the buttresses 14, there has been 15 provided a cover generally indicated at 20, and which comprises an inverted channel member including a web 21 defining a receptacle top wall and a pair of depending sides 22 defining receptacle side walls. Opposite ends of the side walls 20 22 are longitudinally extended, as at 23, to provide laterally-spaced and opposed portions which are adapted to overlie opposite sides of the buttresses 14 when the receptacle is in the receptacle-providing closed position whereby to brace the cover 20 against lateral displacement from the comb back 11. The free lower edges of the side walls 22 and extensions 23 are laterally oppositely inwardly directed to provide flanges 24 which ride in the grooves 15. Specifically, the flanges 24 25 seat against the floors of the shallow groove portions 17 and are slightly spaced from the floors of the deep central portions 16 of the grooves. A central portion of each flange 24 is provided with a laterally inwardly-directed finger 25 which seats against the floors of the central deep portions 16 of the grooves. Likewise, the fingers 25 are adapted to abut the shoulders 18 aforesaid, whereby to limit sliding movement of the cover 20 relative to the comb back 11 in both directions. Likewise, at least one end of the flanges 30 formed on the extensions 23 are oppositely recessed, as at 26, to provide latch detents engageable with the latch dogs 19 to lock the cover 20 in a closed receptacle-providing position.

By providing the stop fingers 25 intermediate the length of the cover 20, the latter is permitted limited sliding movement in both directions until the fingers engage the stop shoulders 18. Thus, not more than half of the floor-providing edge 13 is exposed at any one time, whereby the receptacle is in an open position permitting pins or the like contained therein to be dumped outwardly atop the uncovered portion of the floor 13. It should be noted also that such sliding movement is permitted in either direction, where-

by a double-ended receptacle is provided. Likewise, the provision of a latch 19 and 26 serves to lock the cover 20 in a receptacle-providing closed position so that the contents of the receptacle will not be spilled in case the comb is accidentally dropped on the floor. Likewise, the latch prevents the cover 20 from accidentally sliding relative to the comb back 11 when the comb is in use. Moreover, it should be noted that the receptacle is usable with any of a plurality of like combs provided with the groove 15 and the buttresses 14, whereby the cover 20 may be made of metal or other ornamental material of greater value than the comb proper.

While I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

1. A comb back, comprising a substantially flat upper edge comprising a receptacle floor, a pair of upwardly-directed buttresses carried by said edge in longitudinally-spaced relation and providing receptacle end walls, a channel-shaped cover providing receptacle side and top walls, said comb back being formed with a pair of laterally-aligned and laterally-oppositely-directed longitudinally-extending grooves, said cover including a pair of opposed inwardly-directed flanges slideable in said grooves whereby to mount said cover on said comb back for longitudinal movement relative thereto, said flanges including at least a pair of centrally-located and oppositely inwardly-directed fingers, said grooves each including a relatively deep central portion receiving said fingers therein and relatively shallow end portions receiving said flanges therein, shoulders connecting said end portions with said central portions, said shoulders being engageable with said fingers to limit relative sliding movement of said cover and comb back in both directions, and said cover cooperating with said upper edge and said buttresses to define a receptacle.

2. A comb back, comprising a substantially flat upper edge comprising a receptacle floor, a pair of upwardly-directed buttresses carried by said edge in longitudinally-spaced relation and providing receptacle end walls, a channel-shaped cover providing receptacle side and top walls, said comb back being formed with a pair of laterally-aligned and laterally-oppositely-directed longitudinally-extending grooves, said cover including a pair of opposed laterally-directed flanges slideable in said grooves whereby to mount said cover on said comb back for longitudinal movement relative thereto, said flanges including at least a pair of centrally-located and oppositely inwardly-directed fingers, said grooves each including a relatively deep central portion receiving said fingers therein and relatively shallow end portions receiving said flanges therein, shoulders connecting said end portions with said central portions, said shoulders being engageable with said fingers to limit relative sliding movement of said cover and comb back in both directions, said cover including opposite ends each defined by a pair of laterally-spaced and opposed portions, said portions being adapted to overlie opposite sides of said buttresses with said cover in a closed position whereby to brace said cover against lateral displacement from said comb back, said flanges and said shallow portions of said grooves including interengaging portions providing latches for releasably locking said cover in said closed position, and said cover cooperating with said upper edge and said buttresses to define a receptacle.
